WILLIAM G. MAGOVENY, OF SYRACUSE, NEW YORK, ASSIGNOR TO CROUSE-HINDS COMPANY, OF SYRACUSE, NEW YORK, A CORPORATION OF NEW YORK.

LOCK FOR BOXES.

1,152,116.

Specification of Letters Patent. Patented Aug. 31, 1915.

Application filed June 22, 1911. Serial No. 634,773.

To all whom it may concern:

Be it known that I, WILLIAM G. MAGOVENY, of Syracuse, in the county of Onondaga and State of New York, have invented 5 a certain new and useful Lock for Boxes, of which the following is a specification.

This invention has for its object the production of a lock particularly applicable for electrical conduit outlet boxes, and it consists 10 in the combinations and constructions hereinafter set forth and claimed.

In describing this invention reference is had to the accompanying drawing in which like characters designate corresponding 15 parts in all the views.

Figure 1 is a plan of an electrical conduit outlet box provided with my invention, the cover for such box being open. Fig. 2 is a cross-sectional view of the box and cover 20 therefor provided with my invention. Fig. 3 is a fragmentary view illustrating the bolt of the lock in rear elevation, contiguous parts of the box and cover being also shown. Fig. 4 is a detail view of the bolt 25 of the lock. Fig. 5 is an inverted view of the detached handle.

1 is the conduit outlet box, here shown as rectangular in form in top plan and as provided with extensions at its ends having 30 nipples 2 for connection with conduits enclosing electric wires having an outlet in the box 1 or connected to electrical appliances in the box 1.

3 is a cover for the box 1, the cover being 35 hinged to the rear side of the box at 4.

The lock for holding the cover in its closed position comprises a bolt located on the inside of the box in such position as to occupy a minimum space so as not to interfere 40 with electrical appliances or other contents of the box 1, and a handle located on the cover preferably formed of sheet metal. The bolt 5 consists of a flat bar or plate having its major or intermediate part slidable 45 along the inner face of the cover 1. The front end of the bolt depends from said major or intermediate part substantially perpendicular thereto and terminates in a portion 6 disposed substantially in parallelism with the major part of the bolt and forming a pawl or latch which interlocks with a shoulder 7 on the inner face of the front side of the box 1. Said portion 6 also coacts with an outwardly inclined surface 55 8 on the box above said shoulder for caus-

ing the bolt 5 to latch as the cover approaches its closed position. The bolt 5 is formed with a lengthwise slot 9 through which projects means fixed to the cover for supporting the bolt 5, said means being here 60 shown as in the form of a pin or rivet 10 having a head 11 slidably engaging the lower face of said bolt.

12 is a handle for the bolt and also for the cover, said handle having a stem 13 extending through a slot 14 formed in the cover 3, and extending at right angles to the front and rear sides of the box, said stem 13 extending through a hole 15 in the bolt 5 and being fixed to the bolt 5 in any suitable 70 manner. The handle 12 is also formed with a base 16 slidably engaging the upper face of the cover and large enough to cover the slot 14 in all positions of the handle 12.

The bolt 5 is forced to its operative position by a spring 17 formed of a single piece of wire secured at the opposite ends at 18 to the cover, the intermediate portion thereof being bowed and interposed between the inner face of the cover 3, and the offset lug 80 19 at the rear end of the bolt 5, said lug extending downwardly and then rearwardly from the rear edge of the major part of the bolt, and the intermediate portion of the spring engaging said edge. Preferably the 85 ends of the spring 17 are secured to the cover by widely spaced pins depending from the inner face of the cover and provided with heads forming the lower sides of recesses between said inner face and heads for 90 receiving the spring.

This lock is particularly simple in construction occupies minimum space, and the spring thereof is durable and easily replaceable when broken.

What I claim is:

1. The combination with a box, a cover hinged to the box and having a slot, a bolt formed from a flat plate and having its major or intermediate part engaging the 100 underside of the cover, and its end portions offset therefrom, the front end portion depending from the major part of the bolt and terminating at its lower end in a pawl or latch for engaging the box, the offset rear 105 end of the bolt forming a recess between the same and the underside of the cover, a bowed spring secured at its ends to the cover and having its intermediate portion located in the recess and shouldering against the 110

bolt, and a handle connected to the major part of the bolt and including a stem extending through the slot in the cover and a head mounted on the stem and slideable on the outer face of the cover, substantially as and for the purpose described.

2. In combination in an outlet box, a side wall having a nose at the outer marginal portion thereof presenting a shoulder and an outwardly inclining face, a cover pivotally mounted adjacent the outer edge of the opposite side wall, a bolt formed by a flat plate having its major part disposed parallel to the under face of the cover and in contact therewith, said plate having at its rear end an offset rearwardly extending lug, and at its opposite end a part extending substantially perpendicular to the major part and terminating in a portion disposed substantially in parallelism with the major part and coacting with said shoulder and inclining face, headed members secured to the cover in rear of the plate and spaced widely apart and providing abutments having receiving recesses, a bow spring held at its ends in said recesses and having its intermediate portion in engagement with the rear end of the major part of said plate and confined between the lug thereof and the opposing portion of the cover, and means for holding the bolt in position including a knob connected to the bolt and having a part accessible on the upper side of the cover, substantially as and for the purpose described.
3. In an electric conduit outlet box, the combination with a box proper, having one side provided with a shoulder, and a surface above the shoulder inclining therefrom to-

ward the outer surface of the box proper, of a cover hinged to the opposite side of the box proper and provided with a slot extending at substantially right angles to said sides of the box proper, a bolt consisting of a flat bar having a flat upper face slidably engaging the flat inner face of the cover, the bolt being provided with a lengthwise slot, the front end of the bolt being extended downwardly and coacting with said shoulder and inclined surface, and the rear end of the bolt having a lug extending downwardly and then rearwardly from the rear surface of the bolt, a spring having its intermediate portion held between the lug and the opposing inner face of the cover and coacting with said rear surface of the bolt, a handle covering the first-mentioned slot and slideable on the outer face of the cover and having a stem guided in said first-mentioned slot and fixed to the bolt at a point spaced apart from the slot in said bolt, a pin having one end fixed to the cover and its other end passed through the slot in the bolt and provided with a head slidably engaging a lower surface of the bolt and spaced apart means projecting from the inner face of the cover and supporting the ends of the spring.

In testimony whereof, I have hereunto signed my name in the presence of two attesting witnesses, at Syracuse, in the county of Onondaga, in the State of New York, this 19th day of June 1911.

WILLIAM G. MAGOVENY.
